(57) **CLAIM**

The ornamental design for a personal warming apparatus, as shown and described.

DESCRIPTION

FIG. 1 is a front perspective view of a personal warming apparatus showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an alternate bottom view thereof, showing a release paper layer removed.

The dashed broken line illustrates a perforation and forms no part of the claimed design. The dot-dashed broken line illustrates a through-slit and forms no part of the claimed design. The relatively light gray shade lines on the surface portions indicate contour and not surface decoration.
